CLAIM

The ornamental design for a collar press, as shown and described.

DESCRIPTION

FIG. 1 is a perspective view of one embodiment of the collar press;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a perspective view of the collar press in an open configuration;

FIG. 9 is a perspective view of another embodiment of the collar press;

FIG. 10 is a front view thereof;

FIG. 11 is a rear view thereof;

FIG. 12 is a left-side view thereof;

FIG. 13 is a right-side view thereof;

FIG. 14 is a top view thereof;

FIG. 15 is a bottom view thereof; and,

FIG. 16 is a perspective view of the collar press in an open configuration.

The broken lines shown in the figures represent unclaimed portions of the article and form no part of the claimed design.

1 Claim, 10 Drawing Sheets
